UNITED STATES PATENT OFFICE.

ANGELO DE ROSA, OF UTICA, NEW YORK.

STOVE-GUARD.

1,146,614.

Specification of Letters Patent. Patented July 13, 1915.

Application filed July 28, 1913. Serial No. 721,495.

To all whom it may concern:

Be it known that I, ANGELO DE ROSA, a citizen of the United States, residing at Utica, in the county of Oneida and State of New York, have invented certain new and useful Improvements in Stove-Guards, of which the following is a specification, reference being had therein to the accompanying drawing.

10 My invention relates to an improvement in stove guards, and I declare that the following is a full, clear, concise and exact description thereof, sufficient to enable one skilled in the art to make and use the same, 15 reference being had to the accompanying drawings in which like reference characters refer to like parts throughout.

In my application filed March 25, 1912, Serial Number 685,932, I showed a form of 20 guard and this present construction is an improvement on that construction in that it is more simple and may be adjusted to different conditions.

25 In the drawings Figure 1 is a side view of a stove with a part shown in dotted lines; Fig. 2 is a detailed view of a portion of the members shown in Fig. 1, but in a different position; Fig. 3 is a sectional view showing the latch which holds the guard in closed 30 position, the parts being shown, however, with the cover or guard in open position, while Fig. 4 shows the same parts with the cover in closed position, and Fig. 5 is a partial plan view with the cover or guard 35 opened.

Referring to the figures in detail, A represents the body of the stove and B shows the bracket suitably mounted on the stove which extends forwardly beyond the stove 40 to support a bar or rod C which is common to such stoves. On the bar C is mounted a clasped collar 1 tightened by the screw or bolt 2 and which has a lug 3 on which is mounted a bracket 4. This bracket is apertured longitudinally, as indicated at 5 and 45 7, to permit the adjustment of the cover 9 to different conditions. The cover, referred to generally by 9, comprises end plates 10 and a plate 11, Fig. 3, which is of such a form 50 as indicated in the various figures as to cover the handles or knobs 12 by which the gas is turned on or shut off from the stove. The end-plates 10 of the cover 9, have slots 55 therein, as indicated by 17, which are transverse substantially to the line of the slots 5 and 7, whereby it will readily be seen ad-

justment of the cover may be made upward, downward, forward or backward.

Referring now particularly to Fig. 3, at some suitable point in the length of the rod or tube C is mounted a collar 20 which is secured by screw and nut, indicated generally by 21. This collar has an arm 22 which is slotted as at 23 for the passage therethrough of the latch 24 which has a shoulder therein, indicated at 25. The latch 24 has an enlarged end, as seen at 27, which prevents the latch from passing through the opening in the bar 22 though the latch may be passed through the slot 23 by being tilted when assembling the parts. When the cover 11 is swung from the position shown in Fig. 3 into the position shown in Fig. 4 the gravity of the latch 24 brings the shoulder into engagement with the opening in the 75 arm 22 which effectually closes the cover 11, Fig. 4, from being swung open. In order to release the cover it is necessary to press inward at the free end of the latch 24 in order to disengage the shoulder 25 from the 80 arm 22.

It will be seen by reference to the figures that the cover or guard is provided with openings which are elongated horizontally. When the gas is turned on the handle of the 85 gas-valve projects through an opening in the cover. As the openings are elongated it permits the necessary adjustment of each valve to secure the correct or desired flame, but the handle cannot be swung so far as to 90 shut off the gas entirely. When it is desired to close the gas valve the cover is thrown back by pressing inward on the lower end of the latch which disengages it from the arm 22. When the gas-valves have been 95 properly opened or shut the cover is thrown back into place and is held in locked position, as explained.

Having described my invention, what I claim as new and desire to secure by Letters 100 Patent, is:

1. In a gas stove, the combination of a cover and a bracket supporting the cover and swingably mounted, the bracket having elongated slots extending in one direction 105 and the cover having elongated slots extending in a different direction whereby the cover may be variously positioned relative to the bracket.

2. In a device of the character described, 110 the combination with a gas stove, a fuel supply pipe, burners and valves controlling the

supply to the burners, a cover swingably mounted relative to a gas stove, a slotted arm and a latch pivotally mounted on the cover and extended through the slotted arm, **5** the said latch having a shoulder adapted to engage the slotted arm and hold the cover in closed position.

3. In a device of the character described, the combination with a gas stove, a fuel sup- **10** ply pipe, burners and valves controlling the supply to the burners, of a bracket swing-

ably mounted and a cover adjustably mounted on the bracket to be swung into opened or closed position.

In testimony whereof I have hereunto **15** affixed my signature in the presence of two witnesses.

ANGELO DE ROSA.
